UNITED STATES PATENT OFFICE

JOHN J. TURNER, OF CHICAGO, AND CARL ABSMEIER, OF MAYWOOD, ILLINOIS, AS
SIGNORS TO UNITED STATES GYPSUM COMPANY, OF CHICAGO, ILLINOIS, A COR-
PORATION OF ILLINOIS

MIXING DEVICE

Application filed February 10, 1930. Serial No. 427,100.

This invention relates to a device for mixing cementitious compositions with water.

In the manufacture of plasterboard, tile, and other gypsum or cementitious products with water, the setting time of the gypsum is so controlled by means of accelerators, that a very rapid setting occurs. It is often found desirable to introduce foam and various fibers into the composition by mixing so as to control the properties of the resulting product. Because of the rapid setting of the composition, it is difficult to design a satisfactory mixer because of the fact that the stucco tends to accumulate upon inactive surfaces of the mixer and eventually stops up the action thereof so as to make it necessary to shut down the mixer for cleaning. Considerable difficulty has also been experienced in that lumps of material form which have unmixed centers, the latter not being homogeneously mixed with the other ingredients and forming defects in the resulting product.

An object of this invention, therefore, is to provide an improved apparatus of mixing whereby the water is thoroughly incorporated with the gypsum or cementitious composition.

Another object of the invention is to provide an improved mixer which will not permit stucco to set up on inactive surfaces and will also break up all lumps which might otherwise be formed; also to improve mixing methods and apparatus in other respects hereinafter specified and claimed.

Reference is to be had to the accompanying drawings forming a part of this specification, in which

Fig. 1 is a sectional elevation of the improved mixing apparatus,

Fig. 2 is a plan view of the apparatus,

Fig. 3 is a plan view of one of the discharge gates,

Fig. 4 is a sectional view through the apparatus taken on the line 4-4 of Fig. 1,

Fig. 5 is a sectional view through the apparatus on the line 5-5, of Fig. 1,

Fig. 6 is a sectional view through the apparatus on a large scale, on the line 6-6 of Fig. 2, and

Fig. 7 is a plan view of one of the discharge screens.

The stucco composition to be mixed with water is introduced onto a belt 10 which is allowed to sag near its delivery pulley 11 to form a water pocket. Water is introduced into the pocket and the stucco composition in dry form is introduced onto the belt 10 and drawn through the water pocket. The dry material is thoroughly soaked and moistened by the water, and then is conveyed upwardly above the water level to then pass over the pulley 11, and then down the inclined reach of the belt 12, to pulley 13, where the material is discharged from the belt and dropped into a mixer bowl 14. Shafts 16 and 17 supporting the pulleys 11 and 13 respectively are suitably driven by any means, such as an electric motor not shown, so as to maintain a substantially uniform speed of the belt 10.

The mixing bowl 14 is preferably in the nature of a shallow cylindrical shell formed into sections 18 having flanges 19 connected together by suitable bolts 19a, so that sections 18 can be easily removed for cleaning or repairing without disturbing other parts of the apparatus. The bowl sections 18 rest upon a bottom plate 20 which is preferably formed of cast metal. The plate 20 is preferably provided with a circular tongue 21 formed on its upper surface which engages a similarly shaped groove formed in the bottom of the bowl sections 18, so as to fix the position of the mixing bowl relative to the bottom 20. The bottom plate 20 is provided with outstanding lugs 22 which engage suitable framework 23 arranged to support the mixing apparatus. A plate 24 is rigidly secured across the framework 23.

below the mixing bowl so as to form a support for a plurality of strips of paper 26, such as three in number, which move on top of the plate 24 with a continuous motion so as to receive the mixed cementitious material from the mixing bowl 14, the composite materials then being later formed into plasterboards or wall boards.

The bottom plate 20 is provided with an internal, semicircular raceway 28 which cooperates with a similar semicircular raceway 29 in the inner lower part of the bowl section 18. A frustoconical mixing element 30 is rotatably mounted concentrically with the mixing bowl 14, and the outer periphery of said element 30 is provided with a semicircular raceway 31. A circular space 32 is provided between the outer periphery of the element 30 and the raceway 28 to receive a plurality of balls 33 which roll in the raceways. These balls 33 are preferably but not necessarily composed of a metallic interior for the purpose of giving them weight, and this metallic core is covered by a semi-hard layer of rubber, which has sufficient resiliency to flex slightly and aid in breaking off any encrusting layers of plaster of Paris which may form on their surfaces. These balls aid materially in breaking up any lumps of material which may be formed, and thus insure a uniform and homogeneous mixture of the water introduced through a pipe 34 with the plaster of Paris and other ingredients.

The frusto-conical mixing element 30 is preferably rigidly secured near the bottom of a vertical shaft or spindle 36, the extreme lower end of said shaft being supported in a suitable step bearing 37 which is removably secured by bolts 38 to the bottom plate 20. Suitable openings 40 are provided in the bottom plate 20 so as to prevent the accumulation of any materials under said mixing element 30. Scrapers 41 are mounted diagonally in the lower face of the element 30 for the purpose of preventing any accumulation of material between the metal faces and to prevent the escape of material through openings 40 by continuously scraping the material outwardly into the space 32.

It is desirable to have the shaft 36 and mixing element 30 rotated continuously at a speed of 90 to 150 R. P. M. and for this purpose, a motor 42 is supported upon suitable framework 43, and is connected by a belt 44 to a speed reducer 45 of standard construction. A vertical shaft 46 driven through the speed reducer 45, is provided with a flexible coupling 47, connecting said shaft to the shaft 36. A gear 50 is concentrically mounted about the shaft 36 and a clutch 48 is connected between shaft 46 and said gear, said clutch being operated by a lever 49 to stop or start the rotation

of said gear. The gear 50 meshes with an idler gear 51 which is rotatably mounted on a fixed idler shaft 52. The gear 51 meshes with a larger gear 53 which in turn is secured to a shaft 54 having a pinion 55 secured to the lower end thereof, said pinion meshing with a large internal gear 56 which is rigidly secured to a sleeve 57 concentrically mounted about the shaft 36.

A collar 58 is secured to the lower end of sleeve 57 and is rotatably mounted about shaft 36 just above the mixing element 30. A scraper arm 59 is secured to the collar 58 as by screws 60, said scraper arm having the same shape as the contour of the mixing element 30 so as to scrape said mixing element and prevent the formation of encrusting matter thereon. A second U-shaped arm 62 is secured to the collar 58 diametrically opposite the arm 59, and a semi-flexible arm 63 is secured at its innermost end by a bolt 64 to the arm 62 and midway its end it is loosely received between an upturned forked end 65 formed on the arm 62. The flexible arm 63 is mounted to contact with and scrape the lower surface of a cover 66 which rests upon the mixing bowl, so as to prevent any plaster of Paris from accumulating on the lower face of the cover. A scraper arm 67 is secured to the outermost end of the arm 63, the arm 67 being arranged to scrape the inside of the mixing bowl 14 and prevent the setting of cementitious material on the inner face of said bowl.

The balls 33 provide a grinding and mixing action for the material in the mixer. In order to prevent the passage of any lumps of material onto the moving strips of paper 26, we provide a screen plate 69 below the opening or port 32, one screen being provided for each strip of paper so that for three strips of paper, three screens will be used as shown in Fig. 2. The screens 69 are preferably in the form of a circular plate, having numerous holes or ports 70 formed therein, or screen wire. The screen plate 69 is preferably rotatably mounted on the upper end of a pin 71, which is rigidly fixed in a port casting 77, by set screw 72. The outer periphery of the screen plate 69 preferably has a bevelled edge 73, so that it is positively received in a similarly shaped groove formed in the port casting 77 and prevented thereby from movement and vibration. The screen plates 69 may be fixed rigidly adjacent the bottom plate 20 but are preferably in circular form so that they may be rotated manually for the purpose of moving a used portion of the screen outwardly into position for easy cleaning.

In order to regulate the flow of plastic material through the port 32, we provide a gate 75 which is preferably semi-circular in

shape, and in the form of a flat plate having a bevelled outer peripheral edge 76 engaging a wedge shaped groove formed in the port casting 77, the latter being secured by bolts 78 to the bottom plate 20. A handle 79 is provided on each gate plate 75 so that said gate may be rotated about the central pin 71 to open and close each discharge port. It will be noted that the gate plate 75 is in close contact with the screen plate 69 and the sharp edge 80 of said gate plate serves to scrape off any encrusting material on the bottom of the screen plate, if so desired. In Fig. 2, it will be noted that two additional gates 81 are provided, one on each side of the mixing bowls, these auxiliary gate plates not being provided with screens but merely serving to permit dumping from the mixing bowl of all material if desired and discharging this material to one side of the machine without falling upon the strips of paper 26. These gates are useful when a mixture of improper composition is received in the mixing bowl and which it is desired to dump without using same for the making of board.

In operation, the dry mixture passes along belt 10 through a sloping pocket containing water and is then discharged in a wet condition into the mixer bowl 14 where it falls upon the frusto-conical mixing element 30 which is rapidly rotating and serves to throw the material outwardly into the path of the balls 33 where mixing action is obtained. The scraper arms 59, 63 and 67 mounted upon the collar 58 are caused to rotate in the same direction as the mixing element 30 but at a slower speed of 5 to 40 R. P. M. The apparatus is driven through motor 42, belt 44 and speed reducer 45 and shaft 46 so as to cause the rotation of shaft 36. The sleeve 57 carrying the collar 58 is operated through clutch 48, gears 50, 51 and 53 and pinion 55 meshing with internal gear 56. The material ground up in the mixing bowl 14 by the balls 33 is caused to pass through screen plates 69, the flow of material through the port opening 32 being controlled by gates 75 manually operated by handles 79, said gates also serving to clean the bottom surface of the screen plates 69. The thoroughly mixed material falls upon the moving strips of paper 26.

We would state in conclusion that while the illustrated examples constitute practical embodiments of our invention, we do not wish to limit ourselves precisely to these details, since manifestly the same may be considerably varied without departing from the spirit of the invention as defined in the appended claims.

Having thus described our invention, we claim as new and desire to secure by Letters Patent:—

1. In a mixing device, a mixing container,

a rotary mixing element having mixing surfaces, scraping means closely adjacent to said rotor and adapted to move relative to said rotary element, and balls arranged around the periphery of said mixing element to aid in the mixing of material in said container. 70

2. In a mixing device, a mixing container, a rotor rotatably mounted in said container, scraping means contacting with said rotor 75 and adapted for movement relative thereto, a ball movably positioned adjacent the periphery of said rotor and adapted to aid in the mixing of material contained in said container, and means for discharging the 80 material from said container.

3. In a mixing device, a mixing container, means for introducing material to be mixed into said container, a rotatably mounted mixing element located in said container, a ball movably arranged within said container, said container being provided with an outlet port to permit the discharge of mixed material from said container, and a screen associated with said port and arranged to 90 prevent the passage of lumps of unmixed material from said container. 85

4. In a mixing device, a mixing container, a shaft rotatably mounted in said container, a rotor having a frusto-conical surface, a 95 ball race around the periphery of said mixing element, said container being provided with an outlet port adjacent said ball race, and a ball movably positioned on said ball race and adapted to aid in the mixing action 100 in said container before the material passes through said discharge port.

5. In a mixing device, a mixing container, a cover for said container, a circular mixing element rotatably mounted within said container, a rotary means for scraping the inside of said cover and said container, additional rotary means adapted to scrape the surface of mixing element, said container being provided with an outlet port positioned adjacent the periphery of said rotary element, a ball race associated with said mixing element, a ball movably arranged on said ball race and adapted to aid in the mixing action in said container before the material is discharged from said discharge port. 110 105 115

6. In a mixing device, a mixing container, a circular mixing element rotatably mounted within said container, means for introducing the material to be mixed into said container, scraping means between said rotary mixing element and said container to prevent the passage of material under said mixing element, said container being provided with a discharge port adjacent the periphery of said mixing element, and a screen covering said discharge port and adapted to prevent passage of lumps of un- 120 125 130

mixed material from said container through said port.

7. In a mixing device, a mixing container, a rotary mixing element positioned within said container, said container being provided with an outlet port adjacent the periphery of said rotary element, a rotatably mounted screen plate positioned across said discharge port, said screen plate being adapted to be manually rotated for easy cleaning, and a discharge gate associated with said screen and adapted to regulate the flow of material from said mixing container.
